CLAIM

The ornamental design for a transmission fluid filter, as shown and described.

DESCRIPTION

FIG. 1 is a top plan view of the transmission fluid filter, particularly showing the inventive design thereof, with the angle of the outlet tube at approximately 90 degrees;

FIG. 2 is a left side elevation view thereof;

FIG. 3 is a right side elevation view thereof;

FIG. 4 is a front elevation view thereof;

FIG. 5 is a rear elevation view thereof; and,

FIG. 6 is a bottom plan view thereof.
